UNITED STATES PATENT OFFICE

108,599

DESIGN FOR A SPRAYER PUMP

Rudolph Bernhardt, Chicago, Ill.

Application December 2, 1937, Serial No. 73,313

Term of patent 7 years

To all whom it may concern:

Be it known that I, Rudolph Bernhardt, a citizen of the United States and resident of Chicago, in the county of Cook and State of Illinois, have invented a new, original, and ornamental Design for a Sprayer Pump, such as used in connection with bottles or containers for spraying liquids, of which the following is a specification, reference being had to the accompanying drawing, forming part thereof.

In the drawing,

Figure 1 is a perspective view of a sprayer pump showing my new design;

Figure 2 is a side view of the same; and

Figure 3 is a view similar to Figure 2 but taken at right angles thereto.

I claim:

The ornamental design for a sprayer pump as shown.

RUDOLPH BERNHARDT.
